United States Patent Office

Des. 227,238
Patented June 12, 1973

227,238

PEDESTAL BUILDING STRUCTURE

Alton D. Wheeler, 3940 Fox Meadow,
Pasadena, Tex. 77502

Filed May 18, 1972, Ser. No. 254,846

Term of patent 14 years

Int. Cl. D25—03

U.S. Cl. D13—1 E

Fig. 1

Fig. 2

FIG. 1 is an elevation view of the pedestal building structure; and

FIG. 2 is a top view of the large pedestal building structure shown in FIG. 1.

I claim:

The ornamental design for a pedestal building structure, substantially as shown.
